UNITED STATES PATENT OFFICE.

NATHAN H. SUREN, OF NEEDHAM, MASSACHUSETTS, ASSIGNOR TO GAMEWELL FIRE ALARM TELEGRAPH COMPANY, OF NEW YORK, N. Y., A CORPORATION OF NEW YORK.

ALARM-CONTROLLER FOR SPRINKLER SYSTEMS.

1,169,692.

Specification of Letters Patent. Patented Jan. 25, 1916.

Application filed April 6, 1914. Serial No. 829,886.

To all whom it may concern:

Be it known that I, NATHAN H. SUREN, a citizen of the United States, residing at Needham, in the county of Norfolk and State of Massachusetts, have invented an Improvement in Alarm-Controllers for Sprinkler Systems, of which the following is a specification.

The invention relates to an improvement in alarm-controllers designed to be used in connection with sprinkler and similar systems.

The invention is primarily designed for indicating, through suitable alarm-mechanism the flow of water, whereby a sub-normal pressure condition is produced in the sprinkler pipes, the construction being such as to avoid sounding an alarm upon occurrence of slight fluctuations in the pressure, due, for example, to the condition known as "water-hammer," whereby false alarms are obviated.

The invention, broadly stated, comprehends a check-valve directly controlling communication between what may be termed the supply and service pipes of the system, and a pressure-control element operatively connected with the check-valve which is operated by the supply-pressure and controlled by the service-pressure, said element directly being arranged to govern a circuit-controller for an alarm.

The invention also comprehends the provision of a yielding connection between the check-valve and pressure-control element, whereby the check-valve is caused to remain in engagement with its seat or to be immediately restored if lifted by sudden or momentary fluctuations in the pressure.

The invention also comprehends the provision of a variable movement for the circuit-controller, whereby it is permitted to move bodily through a limited distance, and during such movement to maintain continuity of the circuit, thereby providing for slight movements of the pressure-control element due to water-hammer and the like.

Figure 1 is a central vertical section through the improved alarm-controller, the parts being shown in elevation. Fig. 2 is a side elevation with the end wall removed. Fig. 3 is a horizontal section on line A—B of Fig. 1. Fig. 4 is a horizontal section on line C—D of Fig. 1.

In the embodiment of my invention, as

here shown, 1 represents a casing having a conduit or passage 3, through it, and a supply-pipe 6 communicates with the inlet end of the casing, and the service pipe 7 communicates with the outlet end of the casing, so that the conduit 3, constitutes a direct means of communication between the supply pipe and service pipe. Near the lower end-portion of the casing 1, and within the conduit an inwardly extending annular lip 8 is arranged, which serves as a valve-seat, and said seat is preferably inclined with respect to the transverse line of the case.

A pivotally supported check-valve 9 is arranged to coöperate with the seat 8, and when in engagement therewith, the continuity of the conduit 3 is interrupted. The wall of the conduit 3, adjoining the seat 8, is formed with a recess 10, and the check-valve 9 has arranged on it above said recess, a roll 11, which projects from the edge thereof and when the check-valve is raised said roll will enter and move in said recess thereby to guide and assist in supporting the check-valve; and said check-valve has on its under side a downwardly extended ear, engaging its pivotal connection which also assists in guiding and supporting the check-valve, particularly against downward movement, when elevated.

At the lower end-portion of the casing a lateral extension 2 is formed having a passage 5 through it communicating at one end with the conduit 3, and its other end has fitted into it an extensible element 13, in the form of a hollow cylindrical body having a convoluted wall to admit of longitudinal extension and contraction thereof. The opposing end of the cylinder is closed by a cap 14, having a surface area within the cylinder approximating the surface area of the check-valve 9. The cap 14 is directly connected to the check-valve through the medium of a rod composed of telescopically arranged sections 16 and 17, one end of the rod being centrally connected to the cap and the opposing end to one end of a lever 18, fulcrumed at a point intermediate its length on suitably formed ears arranged on the casing, the opposing end of the lever being pivotally connected to the supply side of the check-valve. A spring 15 encircles said center-rod 16, 17, which is connected at its upper end with the cap 14, and at its lower

end with the lever 18, said spring acting contractively to shorten the connections between the cap and check-valve and thereby hold the sections 16 and 17 of the telescopic rod abutted together at their adjacent ends and the check-valve on its seat or to restore it in case it is lifted by a sudden or momentary change in the pressure.

The cap 14 is provided in its upper portion with a cross-bar 20 to the terminals of which are connected springs 21, 21, secured at their lower ends in any adjustable manner to the wall of the case, as shown in Fig. 2. These springs act to oppose the extension of the cylinder 13, and are adjusted to hold the cap in a predetermined position with the check-valve closed upon its seat at a minimum predetermined pressure in the service pipe.

20 Pivotaly supported on ears 22, projecting from the casing, above the cap 14, is the circuit-controller 23, by which the alarm is controlled. This controller comprises the circuit-terminals which are actuated through 25 a pin 24, of insulating material, extending outwardly from the cap 14, a spring 25 being secured to the circuit-controller and to the partition to insure a downward tendency of the circuit-controller in order that 30 its engagement with the pin 24 will be maintained on slight fluctuations or movements of the head 14. The cylinder 13 and circuit-controller 23 may be inclosed.

An alarm-motor service-pipe 26 leads into 35 the conduit 3, and has its upper open end controlled by a diaphragm 27 carried by the check-valve 9.

The wall of the case above the check-valve is or may be formed with a side-opening 40 adapted to be closed by a removable cover 29, to provide access to the interior of the case when desired.

When the sprinkler-system is empty, the 45 check-valve 9 is positively held open due to the contractive force of the springs 21, 21, and the contractive movement of the cylinder 13, and the consequent operation of the lever 18. When the water is first turned on and passes through the alarm-controller, the conduit 3 provides a means 50 for delivering such water to the sprinkling-system beyond the casing until such system is filled. Immediately succeeding the filling of the system, the incoming water fills the 55 cylinder 13, and extends the same against the pressure of the springs 21, and against the inherent resiliency of the cylinder. This extensive movement of the cylinder continues until the cap 14 has been moved to a 60 position, which, through the medium of the center-rod and lever 18, the check-valve 9 is actuated to close upon its seat; and the cap 14 when thus moved into operative position, that is with the water pressure 65 static, will engage the circuit-terminals to

maintain them closed, which, as here shown, is the non-alarm or normal position, as represented in Fig. 1.

When the check-valve is closed upon its seat it is substantially balanced by the pressure upon both sides of it, and as said check-valve is of substantially the same area as the cap 14, the pressures acting thereupon will tend to hold the check-valve inert. When the pressure in the service pipe or 70 other adjunct of the sprinkler-system becomes sub-normal from any cause, the normal balance of the check-valve is removed, and the pressure on the supply side of said valve is sufficient to force the valve open. 75 This also reduces the pressure in the cylinder 13, permitting contraction of the latter, with the effect to open the circuit-terminals and sound the alarm, and while such contractive movement of the cylinder is 80 purposely not immediate yet is positive, thereby to insure operation of the alarm. In case the pressure in the supply-pipe becomes sub-normal from any cause the pressure in the service pipe will hold the check-valve on its seat, and through the intermediate connections between said valve and the cap 14, said cap will be held in its normal position, notwithstanding the pressure 85 in the cylinder is reduced. In any case 90 fluctuations in pressure, as from water-hammer or other cause will not result in an alarm, which of course would prove a false alarm. This advantage is gained, as here shown, by the connection of the check-valve 9 with the cap 14 through the telescopic-rod connection, and the spring 15, as 95 for instance upon a sudden lifting movement of the check-valve 9, the sections of the telescopic-rod will be separated and the 100 spring 15 will be extended; and upon a sudden lifting movement of the cap 14, said sections of the rod will be separated and the 105 springs 15 and 21 and the corrugated cylinder will or may be extended, but immediately upon cessation of the increased pressure the aforesaid parts will return to normal.

From the above construction, it will be obvious that any abnormal variation in 115 pressure in the service pipes will be indicated by a proper alarm which is caused to operate by a reduction of pressure on the service side of the check-valve, but that false alarms will not be sounded, as the apparatus prevents alarm actuation under slight fluctuations in pressure.

I claim:—

1. An alarm-controller for sprinkler-systems or the like, including a balanced automatic check-valve controlling direct communication between the supply and service sides of said system, having movable balancing means open to the pressure from the supply side of the system connected flexibly 120

125

- to the check-valve and arranged to control an alarm only when the balancing means moves downward, substantially as described.
2. An alarm-controller for sprinkler-systems or the like including a check-valve controlling direct communication between the supply and service sides of said system, and means open to the pressure from the supply side of the system, including an alarm-controlling element, and a yielding connection between said element and check-valve, substantially as described.
3. An alarm-controller for sprinkler systems and the like, including a balanced automatic check-valve controlling direct communication between the supply and service sides of said system, having balancing means open to the pressure from the supply side of the system and connected with the check-valve, and a circuit controller operated when the check-valve opens and the balancing means contracts, substantially as described.
4. An alarm-controller for sprinkler-systems and the like including a check-valve controlling direct communication between the supply and service sides of said system, movable means open to the pressure from the supply side of the system and connected to the check-valve, and a circuit-controller operative by said means, said circuit-controller being mounted for a limited movement in correspondence with the movement of said means, substantially as described.
5. An alarm-controller for sprinkler systems and the like including a check-valve controlling direct communication between the supply and service sides of the system, movable means open to the pressure from the supply side of the system, a yielding connection between said means and the check-valve, and a circuit-controller for an alarm operative by said means, said circuit-controller being arranged for a limited movement in correspondence with the movement of said means, substantially as described.
6. An alarm-controller for sprinkler-systems including a casing formed to provide a conduit forming a communication between the supply and service sides of the system, a check-valve arranged in the conduit, an extensible actuator in open communication with the pressure from the supply side of the system, means to connect said actuator with said check-valve and a circuit-controller for an alarm arranged to be operated by said actuator, substantially as described.
7. An alarm-controller for sprinkler-systems including a casing formed to provide a conduit forming a communication between the supply and service sides of the system, a check-valve arranged in the conduit, a corrugated cylinder closed at one end and its other end being in open communication with the pressure from the supply side of the system, means to connect said cylinder with the check-valve, and a circuit-controller for an alarm arranged to be operated by said actuator, substantially as described.
8. An alarm-controller for sprinkler-systems including a casing formed to provide a conduit forming a communication between the supply and service sides of the system, a check-valve arranged in the conduit, an extensible cylinder open at its lower end to the pressure from the supply side of the system, a cap closing the upper end of the cylinder, a yielding connection between the cap and valve, and a circuit-controller movably supported above the cap, substantially as described.
9. An alarm-controller for sprinkler systems and the like including a casing formed to provide a conduit forming a communication between the supply and service sides of the system, a check-valve arranged in the conduit, an extensible cylinder open at its lower end to the pressure from the supply side of the system, a cap closing the upper end of the cylinder, a lever supported within the casing and connected at one end to the valve, a telescopic rod connecting the opposing end of the lever with said cap, a spring also connecting said opposing end of the lever and the cap and a circuit-controller for an alarm arranged for operation by said extensible cylinder, substantially as described.
10. An alarm-controller for sprinkler systems and the like including a casing formed to provide a conduit forming communication between the supply and service sides of the system, a check-valve arranged in the conduit, an extensible cylinder open at one end to the pressure from the supply side of the system and closed at the opposite end, a yielding connection between said cylinder and the check-valve, and springs connected with the cylinder and arranged to oppose extension thereof, and a circuit-controller for an alarm arranged for operation by said extensible cylinder, substantially as described.
11. An alarm-controller for sprinkler-systems including a casing, a check-valve arranged in the casing and controlling passage of the fluid through the casing from the supply side to the service side of the system, an extensible cylinder open at one end to the pressure from the supply side of the system and closed at the opposite end, a lever supported within the casing and connected at one end to the valve, a telescopic rod connecting the opposing end of the lever and the closed end of the casing, and a spring-pressed yielding circuit-controller mounted in the casing above the closed end of the cylinder, whereby to permit said controller a limited movement in correspondence with the movement of the closed end of the casing, substantially as described.
12. An alarm-controller for sprinkler-

- systems including a casing, a check-valve therein and controlling passage of the fluid through the casing from the supply side to the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, substantially as described.
15. 13. An alarm-controller for sprinkler-systems including a casing, a check-valve therein and controlling passage of the fluid through the casing from the supply side to the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, substantially as described.
20. 14. An alarm-controller for sprinkler-systems including a casing, a check-valve therein and controlling passage of the fluid through the casing from the supply side to the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, substantially as described.
25. 15. An alarm-controller for sprinkler-systems including a casing, a check-valve therein and controlling passage of the fluid through the casing from the supply side to the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, substantially as described.
30. 16. An alarm-controller for sprinkler-systems including a casing, a check-valve therein and controlling passage of the fluid through the casing from the supply side to the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, substantially as described.
- the service side of the system, an extensible cylinder open at one end to the pressure supply side of the system, a cap closing the opposite end of the cylinder, a lever supported within the casing and connected at one end to the valve, a spring-controlled telescopic rod connecting the opposing end of the lever and the cap, and a movably mounted circuit-controller arranged in the casing above the cap, and a spring actuating the circuit-controller toward the cap, substantially as described.
15. An alarm-controller for sprinkler systems including a casing formed to provide a conduit forming communication between the supply and service sides of the system, a check-valve arranged in the conduit and an extensible cylinder opening at its lower end to the pressure from the supply side of the system, a cap closing the upper end of the cylinder, a yielding connection between the cap and valve, said cap and valve presenting substantially equal areas to the pressure, and means controlling an alarm associated with said extensible cylinder, substantially as described.
- In testimony whereof, I have signed my name to this specification, in the presence of two subscribing witnesses.
